INDICATING AND ADJUSTING MECHANISM
FOR MACHINE TOOLS

Harold J. Siekmann and Ross M. Bacon, Cincinnati, Ohio, assignors to The R. K. Le Blond Machine Tool Co., Cincinnati, Ohio, a corporation of Delaware

Original application January 18, 1945, Serial No. 573,321, now Patent No. 2,464,619, dated March 15, 1949. Divided and this application December 8, 1948, Serial No. 64,228

4 Claims. (Cl. 74—473)

1

This is a divisional application of original application Serial Number 573,321, filed January 18, 1945, now patent #2,464,619, issued March 15, 1949.

This invention relates to improvements in headstocks for lathes.

It is an object of our invention to provide a headstock affording a wide range of speeds wherein all speeds are selected by movement of a single control element.

Still another object is to provide an improved single lever indicating and control lever for a machine tool transmission.

A further object is to provide critically positioned detent means for a single lever indicating and control mechanism for a lathe headstock which is smooth in operation and accurate in positioning the shifted elements.

And another object is to provide a single lever control mechanism which is free from hazard and danger regarding catching the operators clothes or when wiping the machine.

Other objects and advantages of this invention will become apparent as the description proceeds.

In the drawings:

Figure 1 is a diagrammatic expanded section through a typical lathe headstock shiftable gear transmission to which this invention is particularly well adapted.

Figure 2 is a diagrammatic fragmentary plan view showing the single lever indicating and adjusting mechanism and the associated gear shifting apparatus.

Figure 3 is an enlarged fragmentary front elevation of the single lever indicating and control mechanism in Figure 2.

Figure 4 is a fragmentary section on the line 4—4 of Figure 3.

Figure 5 is a section on the line 5—5 of Figure 4.

Figure 6 is a section on the line 6—6 of Figure 4.

Referring particularly to Figure 1, the headstock housing 8 has a drive shaft 3 journaled in rib portions 8a and 8b thereof, as by bearings 9 and 10. Shaft 3 is journaled exteriorly of housing 8 in bearings 4 and 5 carried by a bracket 6 attached to housing 8 by screws 7. A pulley 1, grooved for a belt drive as at 2, is journaled upon a portion of shaft 3 within bracket 6 and is adapted for connection and disconnection with shaft 3 by means of a conventional clutch mechanism indicated generally at 1a and adapted to be actuated and controlled by a collar 3a slidable on shaft 3 in a manner well known in the art and as shown, for example, in the patent to Groene, 1,878,495, September 20, 1932.

2

Within housing 8, shaft 3 has affixed thereto the triple gear 11 including gears 12, 13 and 14. A small pinion 15 is also fixed to a splined portion of shaft 3 adjacent bearing 10. An intermediate shaft 19 is journaled within housing 8 on three bearings 16, 17 and 18. This shaft is splined as at 20 between rib portions 8a and 8b and a quadruple gear 21 has a splined internal bore fitting shaft 20 whereby integrally formed gears 22, 23, 24 and 25 of gear 21, may be selectively brought into mesh with gears 12, 13, 14 or 15, respectively, as will be clear from inspection of Figure 1. The portion of shaft 19, between rib 8b and the adjacent headstock housing 8 has a splined portion 28 of reduced size, upon which a compound gear 27, having a correspondingly splined bore, is slidable. Gear 27 consists of a gear 30, a pinion 29 and an intermediate collar having a shifting slot 78. By appropriate sliding of gear 21 by means subsequently described, shaft 19 may be selectively rotated at any one of four different speeds.

A pulley shaft 38 is journaled by bearings 39 and 40 in portions 8a and 8b, respectively. This shaft has a splined section 42 at one end and a pinion 37 fixed to its other end. A pulley 41 having its periphery grooved for belt driving, is mounted for rotation with shaft 38 by means of a bore splined to fit section 42.

Spindle 26 is journaled at its rearward end by a bearing 31 carried in rib portion 8a, and at its forward end by a bearing 32 carried in the forward headstock housing wall. At its rearward end, spindle 26 has a belt pulley 44 fixed thereto. It also has a pinion 94 fixed to its mid-portion, and a large face gear 35 and smaller gear 36, fixed on its forward end.

Compound gear 27 is slidable by means subsequently described, into any one of three positions; first, wherein pinion 29 meshes with face gear 35 to provide, in connection with gears 11 and 21 a range of four slow powerful back gear drive speeds needed for heavy roughing cuts and for turning work of relatively large diameter; secondly, wherein gear 30 is meshed with gear 36 to provide, in connection with gears 11 and 21, a range of four intermediate spindle speeds; and thirdly, wherein gear 30 is brought into mesh with pinion 37 upon shaft 38 to drive pulleys 41, 44 and spindle 26, in connection with gears 11 and 21, over a range of four high spindle speeds. A range of twelve spindle speeds is thus provided which, for example, may be variously distributed between a low of 25 and a high of 1800 R. P. M.

The axes of spindle 26 and of shaft 38 are relatively fixed and there is provided means for

adjusting the tension of V-belts 43. As shown at Figure 1, the pulley 44 is formed with an integral circumferential rib 44a forming one side of one V-groove. An inner ring 45 fits a cylindrical portion of pulley 44 and is triangular in cross-section to form the adjacent faces of the V-grooves. This ring has one or more axially extending slots or keyways on its inner periphery within which fits the protruding end of a pin 46 fixed in the adjacent surface of pulley 44 whereby the ring may have a slight adjustment axially of pulley 44, but is fixed against rotation relatively thereto. A second ring 47 has one side beveled to form the remaining side of the outer or rearward pulley groove. This ring is screw-threaded on the pulley, as shown in Figure 1, and may be locked in a selected position of rotative adjustment by means of a screw 48 in pulley 44, adapted to engage counterbores 49 in ring 47.

When it is desired to tighten belts 43, screw 48 is loosened and ring 47 is turned down on pulley 44. This causes proportional shifting of ring 45, decreases the effective width of the pulley grooves, and causes belts 43 to ride at a greater radial distance from the spindle axis. As a result, the belts are tightened and, since pulley 41 is splined upon shaft 38, it immediately adjusts its longitudinal position in accordance with the new adjustments whereby both belts run true at all times. Likewise, the belts may be loosened by retrograde rotation of ring 47, while the belts may be removed simply by removing the rings 47 and 45. Spindle 26 is provided with the usual face plate 33 and center 34.

A pick off gear 81 is provided for the usual drive to feed box of the lathe. This gear is fixed upon a shaft 82 journaled in the headstock wall and an adjacent rib portion. The shaft 82 is the feeding shaft or output shaft for the power feed take off for actuating the cutting tool of the lathe through the usual mechanism. In effect this shaft 82, together with the usual lathe mechanism for actuating the tool, comprises the feeding means or the feeding power take off from the headstock to actuate the lathe tool relative to the work spindle. This shaft 82 may take the form of a splined feed shaft by having a splined end upon which a composite gear 85 comprising gears 83, 84 is slideable. A second composite gear 88, having gears 86 and 87 is journaled upon shaft 82. An idler shaft 93 is rotatably mounted on suitable bearings in the headstock housing 8 and has fixed thereto the gears 90 and 91, shown as a composite gear 92. A pinion 89 is also secured to idler shaft 93, the arrangement being such that in one position of composite gear 85, large gear 83 meshes with pinion 89, while in the second position (shown at Figure 1), gears 84 and 90 are in mesh.

A shaft 96 having a splined portion 97 is journaled in bearings in rib portions 8a and 8b, parallel to spindle 26 and separate gears 95 and 112 having splined bores, are mounted thereon. Gear 112 is positioned for engagement and disengagement with gear 90, while gear 95 is positioned for engagement and disengagement with pinion 94 on spindle 26. Thus, when gear 95 is in mesh with pinion 94, feeding power is taken from spindle 26 by way of gear 95, shaft 96, gear 112, gear 90 and gear 84 to shaft 82. Or, of course, if a reduced feeding speed is required, then the feeding drive is from pinion 89 to gear 83 and shaft 82.

However, when gear 27 is in mesh with pinion 37 to effect high speed belt driving, the feeding

speeds afforded by way of spindle 26 and pinion 94, as just described, are much too high. Therefore, at this time, we provide a connection whereby reduced feeding speeds are available in proportion to spindle speeds. This connection comprises a gear 111 fixed to the inner end of shaft 96, and in mesh with a gear 109 journaled on a stub shaft 110 fixed in a boss in rib portion 8b. It will be noted that gear 30, in its extreme leftward position of adjustment, meshes with both pinion 37 and with gear 109. Therefore, at this time, assuming that gear 95 has been moved out of mesh with pinion 94, feeding power is transmitted at speeds much reduced in relation to spindle speeds, by way of gears 30, 109, 111, shaft 96, gears 112, 90, 84 (or 112, 90, 89, 83), to shaft 82.

Reversal of shaft 82 is effected by sliding gear 112 on shaft 96 to cause it to mesh with gear 86 of composite gear 88. Therefore, at this time the drive between shafts 96 and 82 is by way of gears 112, 86, 87, 91, 90 and 84 (or 90, 89 and 83), to shaft 82.

The reversing gear 112 may be shifted manually by any suitable controlled means. The three gears 21, 27, and 95 are shifted in a pre-determined sequential relationship by a novel single lever controlled mechanism as best shown in Figures 2, 3 and 4. A rockable and axially slideable shaft 115 is supported at its rear end in a suitable bearing 116 in headstock housing 8 and has a spool 117 fixed thereto which operatively engages a pin 118 of the arm 119 of a bellcrank lever 120 pivotally mounted on a pin 121 carried in the headstock housing 8. The other arm 122 of the bellcrank lever has a pin 123 fixed in its outer end and operatively engaging in the annular groove 124 of the gear 21 so that axial movement of the shaft 115 effects axial shifting of gear 21 to its respective shiftable positions.

Also on the shaft 115 is a shifter lever 125 having a splined bore 126 slideable on the shaft 115 so that it may be locked by the shaft but still the shaft 115 may have freedom of axial movement. An integral arm 127 of the lever 125 has a pin 128 fixed in its outer end which operatively engages in the annular groove 78 of the gear 27. Another lever arm 129 integrally connected to lever 125 is connected by a link 130 to a shifter lever 131 pivotally mounted on a pin 132 carried by the headstock housing. A lever arm 133 contains a pin 134 operatively engaging in the annular groove 135 of the gear 95.

Referring to Figures 3 and 4, a sleeve 136 is journaled within the boss 137 of the headstock housing 8 and is held against axial movement by a collar 138 threadedly engaging the inwardly projecting end of said sleeve, and locked in position thereon by a set screw 139. At its outer end, sleeve 136 is formed with an enlarged portion that is slotted to form ears 140 and 141 between which control lever 142 is pivoted by a pin 143 passing through aligned holes in the ears and lever, and secured to lever 142, by means of a set screw 143a. Lever 142 has a slot 144 formed therein having parallel sides embracing the flattened end of a shaft 145. This shaft has a key 146 slidably engaging an axially-extending keyway 147 formed in sleeve 136, whereby shaft 145 and sleeve 136 are constrained to rotate as a unit but shaft 145 may slide axially relatively to sleeve 136. A packing element 148 is secured within the counterbored inner end of sleeve 136 to effectively seal the inner end of keyway 147.

The flattened end of shaft 145 has a transverse or elongated slot 149 formed therein through which extends a pin 150 passing through and fixed to the adjacent portions of lever 142 whereby angular movement of lever 142 about the axis of pin 143 may be effected to produce a corresponding axial translation of shaft 145. Furthermore, angular movement of lever 142 about the axis of shaft 145 imparts a like movement to sleeve 136.

The several positions of lever 142 in a plane through the axis of shaft 145, are indicated at 142a, 142b, 142c and 142d, Figure 4, and effect corresponding adjustments of the headstock gears 21, 27 and 95. The positions of lever 142 in a plane normal to the axis of shaft 145, are indicated at 142e, 142f and 142g, Figure 3. Positions 142a to 142d, inclusive, are determined by a series of axially spaced notches 151 formed in shaft 145 and positioned to be engaged by a ball or detent 152 positioned within a radially-extending bore 153 in the enlarged external end of sleeve 136 and urged into the respective notches by a spring 154 engaging at its respective ends a plug 155 closing the end of bore 153, and the ball 152. By this construction shaft 145 is yieldingly held in its various positions of axial adjustment when moved thereto by actuation of lever 142.

Sleeve 136 and shaft 145 are held in their several positions of rotational adjustment by notches 156 circumferentially spaced about the periphery of sleeve 136, and positioned to be engaged by a ball or detent 157 located within a radially-extending bore 158 in the adjacent thickened headstock wall. A compression spring 159 engages at its respective ends, a plug 160 threaded into the end of bore 158 and ball 157, whereby the latter is urged into any one of notches 156 and acts to yieldingly hold sleeve 136 and shaft 145 in the selective rotational positions 142e, 142f or 142g. As shown at Figure 4, the inner end of shaft 115 is drilled at 161 to receive the reduced end 162 of shaft 115. After the shafts 115 and 145 are drilled and coupled by a pin 164 they function as a single integral shaft.

By this construction, a definite amount of leverage is provided in the axial shifting of shafts 145 and 115, while the facing parallel surfaces of ears 140 and 141 provide a large bearing area for the relatively movable contacting surfaces of lever 142 whereby smooth easy operation to all positions of said lever is assured.

As will be noted from Figures 2 and 4, an indicator pointer 165 is fixed to a flattened end portion of shaft 145, by a screw 166. The end of this pointer moves over a chart 167, calibrated as shown in Figure 2, to give the resulting spindle speed for each corresponding position of adjustment of lever 142.

While we have described the embodiment of our invention as now preferred by us, numerous changes, alterations, and substitutions of equivalents, will be obvious to those skilled in this art. The foregoing description is therefore to be taken in an illustrative, rather than a limiting sense. We desire to reserve all such changes, alterations and substitutions as fall within the scope of the subjoined claims.

Having now fully disclosed our invention, what we claim as new and desire to secure by Letters Patent is:

1. In an indicating and adjusting device for machine tools having a casing, a spindle, and mechanism for driving said spindle at a plurality

of speeds, in combination, a sleeve journaled in said casing and having external ears forming a slot therebetween, a shaft axially slidable through said sleeve concentric with the axis thereof, a lever pivoted on and between said ears, said lever being pivotally connected to said shaft, whereby swinging of said lever in a first plane normal to the axis of said shaft effects swinging of said shaft and sleeve, and rotation of said lever parallel to a second plane through the axis of said shaft, translates said shaft, yielding detent means between said casing and said sleeve to maintain said lever in adjusted positions in said first plane, yielding detent means between said sleeve and said shaft to maintain said lever in adjusted position in said second plane, a speed chart mounted on said casing, and an indicator pointer being mounted on said shaft indicatively related to said speed chart.

2. In an indicating and adjusting device for machine tools having a casing, a spindle, and mechanism for driving said spindle at a plurality of selective speeds, in combination, a sleeve journaled in said casing and having a projection external of said casing, a shaft axially slidable through said sleeve, connections between said shaft and mechanism to adjust said mechanism to the several spindle speeds on rotation and axial translation of said shaft, a lever pivoted on said projection and connected to said shaft, means connecting said sleeve and shaft for relative axial movement only, yielding detent means between said sleeve and casing and also between said sleeve and shaft, a spindle speed chart mounted on said casing, and an indicator pointer fixed on said shaft.

3. In a single lever control mechanism for axially reciprocating and rocking a shaft connected to shift the gearing of a machine tool transmission, a sleeve journaled in the housing for said transmission, means for connecting said shaft to be rotated by said sleeve and to slide axially relative thereto, a pair of spaced ears forming integral with said sleeve, a control lever having its inner end guided between said ears and pivotally mounted on said ears to one side of the axis of said shaft, an elongated slotted connection between said lever and said shaft located on the axis of said shaft and sleeve, a speed chart fixed on said transmission housing, and an indicating pointer fixed to said shaft and located between said spaced ears of said sleeve cooperating with said chart to indicate the selected speed.

4. In a single lever control mechanism for axially reciprocating and rocking a shaft connected to shift the gearing of a machine tool transmission, a sleeve journaled in the housing for said transmission, means for connecting said shaft to be rotated by said sleeve and to slide axially relative thereto, a pair of spaced ears formed integral with said sleeve, a control lever having its inner end guided between said ears and pivotally mounted on said ears to one side of the axis of said shaft, an elongated slotted connection between said lever and said shaft located on the axis of said shaft and sleeve, a speed chart fixed on said transmission housing, an indicating pointer fixed to said shaft and located between said spaced ears of said sleeve cooperating with said chart to indicate the selected speed, a radially inwardly urged detent means in said transmission housing engaging detent notches on the periphery of said sleeve to position said sleeve in rotary positions in said housing, and radially inwardly urged detent means in said sleeve engag-

ing detent notches in said shaft to position said shaft axially in said sleeve.
